UNITED STATES PATENT OFFICE.

ARTHUR C. CANDLAND, OF PROVO, UTAH.

RAILWAY-TIE AND FASTENER.

1,015,001.

Specification of Letters Patent. Patented Jan. 16, 1912.

Application filed October 3, 1911. Serial No. 652,662.

To all whom it may concern:

Be it known that I, ARTHUR C. CANDLAND, a citizen of the United States, residing at Provo, in the county of Utah and State of Utah, have invented certain new and useful Improvements in Railway-Ties and Fasteners, of which the following is a specification.

The purpose of my invention is to provide a metal railway tie and fastener, therefore, which is economical in construction, light in weight, easily placed and secured in position and which has the broad bearing surface and cushion effect so much desired. These objects I accomplish with the device illustrated in the accompanying drawings in which similar letters of reference indicate like parts throughout the several figures, and which are hereinafter described in the specifications forming a part of this application.

Figure 1 is a longitudinal section through the middle of the tie. Fig. 2 is an isometric view of one of the locking members. Fig. 3 is an isometric view of one end of the tie, parts cut away. Fig. 4 is an isometric view of one of the clamping plates. Fig. 5 is an isometric view of one end of the tie and a portion of a rail in place thereon, a part of the tie cut away.

My tie is made from a sheet of metal, and bent to form an upturned channel 1. Said channel has transverse slots 2, cut in the bottom thereof to receive the bottom portion of the clamps and the locking member 4. Said channel also has open cuts 5 in the upper edges of the sides within which cuts the base flange of the rail A is placed and within which cuts, the shoulder 9 of the clamps 3 is fitted. Blocks of wood or fibrous material 7 are placed within each end portion of said channel 1 between the cuts 5, and are held therein by the said clamps 3, and on which the rail A is made to rest. The said blocks extend above the bottom of the said cuts 5 to prevent the rails from contacting with the sides of the channel 1, and to supply the resiliency or cushion effect under the rails. The said clamps 3 are each made from a sheet of metal and are in thickness practically one-half the width of the said transverse cuts 2, and each has a portion 8 thereof bent at an angle corresponding to the angle of the base flange of the rail. The upper portion of each clamp 3 is left wider than the said channel 1, to form a shoulder 9 on each side. The bottom por-

tion 11 of each of said clamps is cut to fit within the said transverse slots 2, and centrally located in each of said clamps is cut a slotted opening or hole 10 having its edges beveled. The locking members 4 are cut from a sheet of metal practically the same thickness as the said clamps 3 and in width the same as the portion 11 of said clamps. At one end they are bent upon themselves to form a shoulder 12, and centrally through said locking members are cut slotted openings 13, each having its edges beveled. The said slotted openings 10 and 13 are so located in said clamps and locking members respectively, that when the said clamps are placed within the said channel with the portions 8 engaging the base flange of the rail A, and the bottom portion 11 in the said slots 2, and the said locking members are placed within said slots 2 with the said shoulder 12 engaging the bottom of said channel, and with their sides adjacent the said clamps 3, the said slotted openings 10 and 13 only partially register. Within the opening 14 in said blocks 7 and through the partially registering holes 10 and 13 is horizontally placed a bolt 15 having a cone-shaped head 16 on one end and a portion of the other end threaded. On said threaded end of said bolt and within the said slotted openings 10 and 13 is fitted a frusto-conically shaped nut 17. If it is desired to insulate the rail A, strips of insulating material 18 are placed between the said block 7 and the base of the rail with the edges bent to fit between the said clamps 3 and the base of the rail. With the locking members engaging the bottom of the channel the turning of the said nut 17 on the said bolt 15 in the direction to tighten the said bolt, will cause the sliding of the nut and of the head of the bolt in the partial registering openings 10 and 13, this will draw the said clamps 3 down and they will hold the rail firmly on the tie. The seating of the broadest portion of the clamps 3, at the shoulder 9, in the open cuts 5 will prevent the spreading of the rails. The contact of the nut within the beveled portions of the said openings 10 and 13 will act as a lock and prevent the nuts 17 from jarring loose.

Having thus described my invention I desire to secure by Letters Patent and claim:

1. A railway tie and fastener consisting of an upturned metal channel, spaced apart

- transverse slots in the bottom of said channel, open cuts in the edges of said channel, cushion blocks in said channel of the same length as the space between the said transverse slots and thicker than the height of the said channel at said open cuts and having a horizontal opening therethrough, clamps having an elongated beveled opening in each and a portion of each bent to engage the base flange of a rail, a lug on the bottom of each of said clamps adapted to fit within one of said transverse slots, extended portions of said clamps forming lugs adapted to engage within said open cuts to prevent lateral outward movement of said clamps, locking members having a portion of each bent upon itself and adapted to fit within one of said transverse slots and at the side of one of said lugs on the bottom of said clamps, partial registering elongated slots in said clamps and said locking members having the top and bottom of each slot outwardly beveled, a bolt having a cone shaped head placed horizontally through said elongated slots and said cushion blocks, and a frusto-conically shaped nut on said bolt and adapted to be operated within said partially registered slots.
2. In a railway tie and fastener the combination of an upturned metal channel having transverse slots in the bottom thereof, clamps adapted to extend through said slots and with the upper portion of each bent to engage the base flange of a rail, an elongated circular opening in each of said clamps having the top and bottom thereof outwardly beveled, locking members adapted to engage the bottom of said channel and having an elongated circular opening in each with the top and bottom outwardly beveled and with the sides of said opening registering with the sides of the opening in the clamp adjacent and with the top and bottom not registering when the said clamps and locking members are in position, cushion blocks between each pair of clamps having a horizontal opening therethrough, a bolt through said clamps, said locking members and said cushion block to bind them together having a cone shaped head thereon, and a frusto-conically shaped nut on said bolt adapted to slide in said partially registering openings in said clamps and locking members to make the said openings more nearly register.
3. In a railway tie and fastener the combination of an upturned metal channel, transverse slots in the bottom thereof, blocks between said transverse slots, clamps engaging the base flange of a rail each having an elongated circular opening therein with the top and bottom thereof outwardly beveled and adapted to be moved vertically in one of said transverse slots, locking members adapted to engage the bottom of said channel and each having an elongated circular opening therein with the top and bottom outwardly beveled and with the sides of said opening registering with the sides of the opening in the clamp adjacent but with the top and bottom not registering, and a bolt and conically shaped nut thereon adapted to bind said clamps and locking members on said blocks and to draw said clamps downward as well as inward and to cause said openings to more nearly register.
- In testimony whereof I have affixed my signature in presence of two witnesses.
- ARTHUR C. CANDLAND.
